TW 230629-0001 * 4/2024

Primary Examiner — Paula Allen Greene

(57) **CLAIM**

The ornamental design for a wireless intercom headset, as shown and described.

DESCRIPTION

FIG. 1 is a front view of wireless intercom headset;

FIG. 2 is back view thereof;

FIG. 3 is a left view thereof;

FIG. 4 is a right side view thereof;

FIG. 5 is a bottom view thereof;

FIG. 6 is a top view thereof;

FIG. 7 is a perspective view thereof; and,

FIG. 8 is another perspective view thereof.

The broken lines depict portions of the wireless intercom headset that forms no part of the claimed design.
